CONSTRUCTION BLOCK

Leon Frehner, 2129 S. 2000 East,
Salt Lake City, Utah 84106

Filed May 31, 1968, Ser. No. 12,164

Term of patent 14 years

Int. Cl. D25—01

U.S. Cl. D18—2

FIG. 1

FIG. 2

FIG. 3

FIG. 5

FIG. 4

FIG. 6

FIGURE 1 is a perspective representation of a construction block embodying my new design as viewed from above the block;

FIGURE 2 is an end elevation view of FIGURE 1;

FIGURE 3 is a top plan view of FIGURE 1;

FIGURE 4 is a bottom plan view of FIGURE 1;

FIGURE 5 is a transverse cross-sectional view taken along lines 5—5 of FIGURE 3; and

FIGURE 6 is a longitudinal cross-sectional view taken along lines 6—6 of FIGURE 3.

I claim:

The ornamental design for a construction block, substantially as shown.
